UNITED STATES PATENT OFFICE

2,543,477

KINESCOPE FOR THE REPRODUCTION OF
COLOR IMAGES

George C. Sziklai, Princeton, N. J., and Alfred C. Schroeder, Feasterville, Pa., assignors to Radio Corporation of America, a corporation of Delaware

Application July 29, 1948, Serial No. 41,294

12 Claims. (Cl. 250—164)

1

This invention relates to the reproduction of color images and more particularly, but not necessarily exclusively, to a color television system or the like in which images in substantially their natural color are produced by electronic means.

In accordance with this invention, colored light is obtained by altering the effective velocity of the scanning cathode ray beam of a cathode ray image producing tube in the region of the target area by physically retarding the velocity of the electrons by predetermined amounts by means of mechanical barriers or the like.

The theory of operation of this invention can perhaps best be understood after a brief review of the electron penetration phenomenon.

An excellent treatise on the subject is H. Bethe's "The Theory of Transmission of Fast Corpuscular Rays Through Materials" which may be found in the "Annalen der Physik," vol 5, 1930, beginning on page 325.

In this paper, considering electrons as the particles, the ray equation may be simplified to a form:

$$v_0^4 - v^4 = \frac{16Je^4N}{m^2} BX = K \text{ (a constant)}$$

where

v_0 is the initial velocity of the electron,
 v is the velocity after the electron traveled X distance in the material,
 e is the charge of the electron 4.77×10^{-10} ESU,
 m is the mass of the electron 9.04×10^{-28} gram,
 N is the number of atoms per unit volume of the material, and
 B is the retardation factor of the material.

Mr. Bethe gives the values for the retardation factor B (Bremsvermogen) for several materials, such as 18.7 for aluminum, 48.4 for gold, etc. Considering that the energy released in the solid is

$$\frac{m(v_0 - v)^2}{2} = R$$

it is easily seen that unless v is considerably smaller than v_0 , the energy of the electron is going to be released beyond the layer (in this case the energy will be absorbed by the glass support), since:

$$R = \frac{m}{2} (v_0^2 \pm 2\sqrt{v_0^2 - v^2} K \pm \sqrt{v_0^4 - K^2})$$

which is a function containing a maxima.

Thus considering a layer of phosphor with a barrier of a given K value bombarded with a

beam of increasing velocity, at first the radiation will be zero since the beam does not penetrate the phosphor, then at a value $K=v_0^4$ most of the energy will be absorbed by the phosphor, beyond which the loss of velocity becomes smaller and the energy lost will shift beyond the phosphor.

It will be seen from the above discussion that contrary to the obvious concept, the light radiation does not necessarily increase with the velocity of the impinging electrons but reaches a maximum and then is reduced.

It will be seen, therefore, that differently colored lights may be produced in a stacked or composite screen arrangement wherein the velocity of the electrons traveling through the screen is controlled in such a manner that its most efficient light producing velocity will be at the location of the selected color light producing phosphor or at the phosphor with the properly chosen associated light filter.

This particular principle has, of course, been recognized heretofore for the production of colored light by electron bombardment. An electron sensitive photograph plate may be found well shown and described, for example, in the U. S. patent to E. G. Ramberg, No. 2,442,961, dated June 8, 1948, wherein electrons at controlled velocities are made to impinge upon a layered screen. The velocities are so chosen that the maximum efficiency of each of two velocities produces a maximum of radiation in one of two selected component color light producing mediums.

This fundamental principle of colored light production is also recognized as being applicable to television image reproduction. An arrangement of this sort may be found in the copending U. S. application of Vladimir K. Zworykin entitled "Kinescope for Color Television," Serial No. 739,503, filed April 4, 1947.

In the copending application of Zworykin referred to immediately above, the velocity of the electrons impinging on a multiple layer of screen is controlled in accordance with component color information which is transmitted together with video information.

According to this invention, a novel arrangement is provided for color selection. In the practice of this invention, a cathode ray tube is employed including an electron gun for forming an electron beam. A beam electron velocity control electrode is arranged to receive image color information and a target area consisting of a plurality of color producing light areas is spread

over the target area. A material having different predetermined physical properties is employed to retard the electron beam to predetermined different amounts. This material covers the target area. The amounts of electron retardation correspond to selective color representation associated with similarly representative light producing areas. The color of the light produced may then be controlled by the signal applied to the beam electron velocity control electrode. Images may then be formed in the usual manner of scanning familiar in the television art.

A primary object of this invention is to provide for the production of colored light and colored images without resorting to mechanical rotating devices.

Another object of this invention is to provide for improved color television image reproduction.

Another object of this invention is to provide a novel electron beam target for an image producing tube.

Other and incidental objects of the invention will be apparent to those skilled in the art from a reading of the following specification and an inspection of the accompanying drawing in which:

Figure 1 illustrates schematically one form of this invention;

Figure 2 illustrates graphically the operation of this invention;

Figure 3 illustrates schematically another form of this invention;

Figure 4 illustrates schematically still another form of this invention; and

Figure 5 shows by block diagram this invention as applied to television image reproduction.

Turning now in more detail to Figure 1, there is illustrated schematically a source of electrons 1 which are directed toward an electron target 3 which includes a white light producing phosphor 5 and a series of elemental color filters 7, whose color is indicated by appropriate cross-hatch.

Between the source of electrons 1 and the phosphor or other luminescent material 5, there is positioned a mechanical barrier 9 whose thickness, it will be seen, is dependent upon which of the several component color filters with which it is associated. For example, for each of the green filter elements the mechanical barrier is of the minimum specific amount. However, for each of the blue filter elements the thickness of the mechanical barrier is of the specific amount, while for each of the red filter elements the thickness of the mechanical barrier is still a third predetermined amount. Although a barrier having different thicknesses is shown, according to another form of this invention a barrier having uniform thickness but other different physical characteristics is employed.

Before an attempt is made to explain the operation of the invention shown in Figure 1, a brief reference to the graphs of Figure 2 will be made.

In Figure 2, the light producing effect of electrons impinging upon a luminescent material will be seen not to be directly in proportion to their velocity, but will produce a maximum of luminescence at one particular velocity and drop in light producing effect if the velocity of the electrons is increased above that predetermined amount. In the graph shown in Figure 2, the ordinate R is indicative of light production, while the abscissa V is indicative of the velocity of the electrons.

From the above explanation and illustration it will be understood that if the velocity of the electrons from their source is controlled in accordance with several selected component color representations, the mechanical barrier will cause to be produced a luminescence only behind that barrier which retards the velocity of the electrons to the amount which produces a maximum luminescence in the luminescent portion of the screen. It will be seen, therefore, that color selection may be obtained by utilizing appropriate color phosphors or appropriate color filters adjacent to each different thickness of barrier.

Figure 2 is a graphic representation of the third equation given above.

Turning now to Figure 3, there is illustrated another form of this invention wherein the mechanical barrier takes a different form. In the form of the invention shown in Figure 3, the luminescent material 11 is surrounded by a transparent electron barrier 13. The combination of the luminescent material and the barrier will form a sphere. It will be seen that by controlling the size of the sphere, the mechanical retardation can be controlled. It is therefore possible, by coating the sphere with appropriate color filter material, to obtain the effect shown in the form of the invention illustrated in Figure 1. Thus, as illustrated, by employing several different size spheres any selected component color may be produced.

A transparent support member 15 such as glass or mica is provided.

Although specific values for electron velocity are illustrated, they are by way of example only. More detail regarding control of velocity is given in connection with Figure 5.

Turning now to Figure 4, there is shown still another form of this invention wherein the electron retarding elements also perform the function of color filtering.

It will be seen that each of the green transparent barriers, although irregular in size and irregular in position, are all of a predetermined thickness while the blue transparent barriers are of another predetermined thickness. Likewise, the red transparent barriers are of still another thickness. It will thus be seen that if the observation is made from the direction of source 1 of electrons, the color of the light will depend upon the color of the filter at which point the electrons intercept the barriers.

The size of the barriers shown in the drawings is greatly exaggerated. The random distribution, if desired, may be accomplished by etching, plating, spraying, sputtering, etc.

One suitable method for constructing a target of this nature is outlined below.

Once the composite surface of phosphor, barrier and support is made, a layer of photosensitive gelatin is placed on the empty side of the support and the surface is exposed to electron bombardment of a velocity capable of penetrating through the thinnest barrier layer. The parts of the screen under the thin portion will flow and expose the photosensitive layer. After proper processing, the exposed portions of the gelatin will be green (or any other primary additive color). Next a higher velocity beam is scanned over the barrier, releasing its energy in the phosphor behind the medium thickness barrier and exposing a second layer of photosensitive gelatin which may then be processed to appear blue. Then in a similar manner with an even

higher velocity electron beam, a third gelatin layer is exposed and processed into a random color filter of the third additive primary color. A color filter is thus made, corresponding to the various areas of the phosphor that glow under selective excitation by different velocity electron beams. If the complete surface is now scanned successively with three different velocity electron beams, the screen will appear successively in the three primary colors.

In Figure 5 there is shown a television receiving apparatus having an image producing device in the form of a cathode ray tube 17 provided with the novel target arrangement of this invention, indicated generally by reference character 3, for producing images in color in accordance with the invention. The tube 17 is equipped with a cathode ray gun structure 1 for developing a beam of electrons shown conventionally and indicated by reference character 19. The gun 1 is provided with a control electrode or a grid 21 for modulating the beam 19 which is focused within the depth or thickness of the target device 3. A horizontal (line) and vertical (field) deflecting coil yoke assembly is indicated generally by reference character 23, and the horizontal and vertical deflecting coil assemblies therein are connected to horizontal and vertical deflection generators 25 and 27 respectively to produce scanning action of the beam 19 in a manner which is by now well known. This scanning action is to be maintained substantially constant in area. A television receiver arranged generally in this manner is shown in U. S. reissue patent to Carlson, No. Re. 20,700, granted April 19, 1938. The deflection and control circuits shown and described therein and in a U. S. patent to Tolson et al., No. 2,101,520, granted December 17, 1937, or in the U. S. patent to Vance, No. 2,137,039, granted November 15, 1938 may be employed in connection with the tube 17 of this invention. Synchronization may be maintained in accordance with the arrangement disclosed and claimed in the copending U. S. application of Wright et al. entitled "Beam Deflection Control For Cathode Ray Devices," Serial No. 699,536, filed September 26, 1946, now Patent Number 2,460,112, issued on January 25, 1949. The various electrodes of the electron gun 21 (not all shown) of the tube 17 are to be supplied as usual with suitable operating potentials.

A radio receiver 29 suitable for the reception of television signals from a more or less distant transmitter and equipped with the usual selective circuits, amplifiers and a demodulating device is connected, as shown, so that its output is furnished to a video signal separator and amplifier 31. The demodulated signal from the radio receiver 29 will provide sets of video signals sequentially representing the scanning of an original in several primary colors. In the illustrative arrangement, scanning of the original in any three selected primary or component colors, such as the additive red, blue and green, is assumed for purposes of illustration. Any three colors may be selected so long as they are widely separated spectrally in the I. C. I. color triangle and no two of them can be added together to produce the third, but all add together to produce white.

Transmitters for scanning images and objects in this manner are known and may comprise separate scanning devices, one for each color, operating synchronously; or the original view or object may be scanned sequentially in the manner shown in U. S. Patent 2,413,075 granted to

O. H. Schade, December 24, 1946, or U. S. Patent 2,297,524 to E. I. Anderson, granted September 29, 1942.

The demodulated signal from the radio receiver 29 is applied to a sync separator 33 which separates the horizontal (line) and the vertical (field) sync pulses normally present in the demodulated television signal so that these may be applied to the horizontal and vertical synchronizing controls 25 and 27 respectively. This general arrangement for synchronizing a receiver is commonly used in the art and, for instance, is shown in detail in the Carlson reissue patent referred to above and has been described herein merely for the sake of completeness of the disclosure.

The cathode ray tube 17 includes an electrode 35 which may be in the form of a fine wire grid and is preferably placed outside of the focus of the beam 19. This electrode 35 may be of the type shown in U. S. patent to Beers, No. 2,385,563, granted September 25, 1945, for example. The effect of the grid 35 on the beam at its focal point may be substantially eliminated as described in the Beers patent. It should be understood, however, that the electrode 35 may be in the form of a metallic film or the like which is not impervious to the electron stream of the beam. In the present invention this grid 35 is in communication with a source of relatively high positive potential, such as an appropriate terminal on the power supply unit 37 for the cathode ray tube 17. A connection to the power supply unit is shown diagrammatically and is indicated at 39.

In accordance with the invention, the velocity of the beam 19 in the region of the target 3 is to be altered by an electrode 41. In order to maintain the image size constant the beam stiffness and hence the deflection sensitivity is maintained constant by the grid 35 just described. This grid maintains a constant stiffness of the beam irrespective of voltage changes on the electrode 41.

Having thus described the invention, what is claimed is:

1. An image reproducing system comprising in combination a cathode ray tube including an electron gun for forming an electron beam, a beam electron velocity control electrode arranged to receive image color information, a target area consisting of a plurality of different selected component color light producing areas spread over said target area in mosaic, a material having different predetermined physical properties to retard the velocity of said beam by predetermined different amounts said material positioned between said target area and said electron gun, said predetermined amounts corresponding to selected component color representations, and wherein all material having like physical properties is positioned adjacent areas producing one only of said different selected component color lights and in the path of said electron beam.

2. A color television system employing image color information signals comprising in combination a cathode ray tube including an electron gun structure for forming an electron beam, a beam intensity control electrode and a beam electron velocity control electrode arranged to receive said image color information signals, a target area consisting of a plurality of different selected component color light producing areas spread over said target area side by side, a material positioned in the path of said electron beam and having different predetermined physical properties to retard the velocity of said beam by pre-

determined different amounts, said predetermined amounts corresponding to selected component color representations, and wherein all material having like physical properties is positioned adjacent areas producing one only of said different selected component color lights and in the path of said electron beam.

3. An image reproducing system for color television comprising in combination a cathode ray tube including an electron gun for forming an electron beam, a beam electron velocity control electrode arranged to receive image color information, a target of luminescent material, a plurality of different selected component color light filters each of image elemental area spread over said target area, a mechanical medium barrier positioned between said target area and said electron gun having different predetermined physical properties to retard the velocity of said beam by predetermined different amounts, said predetermined amounts corresponding to selected component color representations, and wherein all of said medium having like physical properties is positioned adjacent filters of one only of said different selected component color and in the path of said electron beam.

4. An image reproducing system for color television comprising in combination a cathode ray tube including an electron gun for forming an electron beam, a beam electron velocity control electrode arranged to receive image color information, a mosaic target area consisting of a plurality of different selected component color light producing areas spread over said target area, a material positioned in the direct path of said beam having different predetermined thicknesses to physically retard the velocity of said beam by predetermined different amounts, said predetermined amounts corresponding to selected component color representations, and wherein all material having like thicknesses is positioned adjacent areas producing one only of said different selected component colors and in the path of said electron beam.

5. An image reproducing system for color television comprising in combination a cathode ray tube including an electron gun for forming an electron beam, a beam intensity control electrode and a beam electron velocity control electrode, said beam electron velocity control electrode arranged to receive a potential depending upon the image color information of the point under scan-
sion, and a mosaic luminescent target, the color of luminescence depending upon the velocity of impact of said electrons, said target including a material positioned in the path of said beam and having different predetermined physical properties to retard the velocity of said beam by predetermined different amounts, said predetermined amounts corresponding to selected component color representations.

6. An image reproducing system for color television comprising in combination a cathode ray tube including an electron gun for forming an electron beam, a beam intensity control electrode and a beam electron velocity control electrode, said beam electron velocity control electrode arranged to receive a potential depending upon the image color information of the point under scan-
sion, and a luminescent target, the color of luminescence depending upon the velocity of impact of said electrons, said target including a material having different predetermined physical thickness to the path of said beam to retard the velocity of said beam by predetermined different

amounts, said predetermined amounts varying across the target area corresponding to selected component color representations.

7. An image reproducing system for color television comprising in combination a cathode ray tube including an electron gun for forming an electron beam, a beam intensity control electrode and a beam electron velocity control electrode, said beam electron velocity control electrode arranged to receive a potential depending upon the image color information of the point under scan-
sion, and a luminescent target, the color of luminescence depending upon the velocity of impact of said electrons, said target including a material having different predetermined physical thickness across its face to retard the velocity of said beam by predetermined different amounts, said predetermined amounts corresponding to selected component color representations, and wherein all the material having the same thickness is positioned adjacent to the same color luminescent portion of the target said material being positioned between said target and said electron gun.

8. A colored light producing system comprising a cathode ray tube including an electron gun for forming an electron beam, a beam electron velocity control electrode arranged to electrically receive color information, a target area consisting of a plurality of different selected component color light producing areas spread side by side with respect to the direction of said beam over said target area, a material having different predetermined physical properties to retard the velocity of said beam by predetermined different amounts, said material being positioned on the gun side of said target area, said predetermined amounts corresponding to selected component color representations, and wherein all material having like physical properties is positioned adjacent one of said different selected component color light producing areas and in the path of said electron beam.

9. A colored light producing system comprising an electron discharge device, an electron velocity control electrode arranged to electrically receive color information and to impart to said electrons a velocity dependent thereon, an electron target area consisting of a mosaic of different selected component color light producing areas spread over said target area, a material having different predetermined physical properties to retard the velocity of said electrons by predetermined different amounts, and wherein all material having like physical properties is positioned adjacent one of said different selected component color light producing areas and within the path of said electrons.

10. An image reproducing system for color television comprising in combination a cathode ray tube including an electron gun for forming an electron beam, a beam electron velocity control electrode arranged to receive image color information, a target of luminescent material, a material positioned between said target and said gun and spread over said target area having different predetermined physical properties at different points across the area of said target to retard the velocity of said beam by predetermined different amounts, said predetermined amounts corresponding to selected component color representations, and wherein said material also has different light color filter properties depending upon its physical properties.

11. An image reproducing system for color

television comprising in combination a cathode ray tube including an electron gun for forming an electron beam, a beam electron velocity control electrode arranged to receive image color information, a target of luminescent material, a material spread over the inside of said target area having different predetermined thicknesses across the target area to retard the velocity of said beam by predetermined different amounts, and wherein said material also has different color light transmission properties depending upon its thickness.

12. A colored light producing system comprising a cathode ray tube including an electron gun for forming an electron beam, a beam electron velocity control electrode arranged to electrical-
15. 5 receive color information, a material spread over the inner surface of said target area having different predetermined physical properties at different points across the face of said target

area to retard the velocity of said beam by predetermined different amounts, and wherein said material also has different light color filter properties depending upon its physical properties.
